original patent but forms no part of this reissue specifi-
cation; matter printed in italics indicates the additions
made by reissue.

ABSTRACT OF THE DISCLOSURE

*Laser employing rod pumped by light from chemical
reaction explosion or light-emitting shock-wave generated
in ionizable gas by such explosion. Rod may be in same
container as explosive material and gas or in adjacent
container with rupturable wall.*

This invention relates to lasers and more particularly to devices for pumping lasers to obtain higher level energy outputs.

An optical maser, or laser, provides a coherent light output beam of highly parallel light rays which are capable of traveling over extreme distances with little divergence. The operation of a laser is based on the extension of maser principles to permit operation in the light spectrum. The laser transforms broadband energy into energy of a single spectral line making it possible to obtain coherent light. Laser operation requires an active material that will produce stimulated emission of radiation, an excitation source that pumps power into the active material, and a resonant structure. The active material, a ruby rod for example, is constructed so that light *irradiated* [eradiated] by photons of the active material stimulates more photons to *irradiate* [eradiate] and intensify the light. Emitted photons trigger additional ions to emit photons in phase with the emitted photon. This in-step radiation causes the individual radiations of photons to radiate their energy in phase, that is, coherently. The resonant features of the optical cavity of the active material cause the light radiated to be reflected back into the material many times. This light, being of a natural frequency of the active material, stimulates more photons to radiate and thereby intensify the light. Due to the amplification caused by the photons stimulating the emission of other photons of the same wavelength, rays comprising photons of the strongest wavelength become predominant over other wavelength rays. This action makes the laser output monochromatic.

Lasers which are developed for use in high power devices require efficient and high energy output pumping sources. Since the active material requires concentrated light energy, the pumping source must provide a high intensity pulse of light. In many applications where space and weight parameters are critical, the pumping source for a laser is required to be as small and light as possible while still providing the necessary high excitation energy for the active material.

Present day pumping sources for lasers utilize a source of electrical power to generate optical pumping radiation for the active material. The means for converting the electrical energy to light energy suitable for pumping the laser material usually takes the form of a flash tube or the like which provides a high intensity light source upon receipt of an electrical pulse. Since available sources of electrical energy such as batteries and alternating current generators do not provide a high voltage source, high

2

energy storage devices such as capacitor banks are required to store electrical energy at high potentials to excite the flash tube which provide the light energy to the active material. High voltage output capacitor banks are necessarily large, [and] cumbersome, and inefficient. Thus, the size of the pumping source requires the laser to be operated in an environment where space and weight are not critical. Additionally, the requirement of high energy light source necessitates the generation of electrical potentials in the kilovolt range which, in turn, complicates the design *required* to protect personnel and prevent leakage of high voltage. Accordingly, it is an object of this invention to provide an improved pumping source for a laser.

15 The device of the present invention provides a high intensity light source for pumping the laser material without the use of electrical energy. A high power, efficient source of energy is provided which directly produces light energy for pumping the laser material. Large and cumbersome capacitor circuits for storing electrical energy are not needed and no means are required for handling extremely high electrical potentials. A small and lightweight pumping source is realized which significantly contributes to the reduction in size and weight of the entire laser structure making possible applications in the air and on the ground heretofore not known in the art.

20 According to another aspect of the invention light for pumping a laser rod is produced by the ionization of a gas in response to the shock wave produced by a chemical reaction explosion.

25 It is therefore another object of this invention to provide a pumping source for a laser devoid of electrical energy excitation.

30 It is a further object of this invention to provide an improved pumping source for a laser.

35 It is still another object of this invention to provide a chemical pumping source for a laser.

Other objects of invention will become apparent from the following description read in conjunction with the accompanying drawings, in which:

40 FIG. 1 is a sectional view partly in schematic of a laser device embodying the principles of this invention.

FIG. 2 is a perspective view of the laser device of FIG. 1.

45 FIG. 3 is a perspective view of a laser device according to an aspect of the invention in which an elliptical configuration is utilized.

FIG. 4 is a sectional view of the elliptical laser device of FIG. 3.

50 FIG. 5 is a sectional view of another aspect of the invention in which an explosively produced plasma is utilized as the light source.

FIG. 6 is a sectional view of a laser according to another aspect of the invention in which the light source is generated by an explosive, and

55 FIG. 7 is a sectional view of a laser showing another way of explosively generating a light source.

According to one [a material] aspect of the invention, a system is provided for the amplification of light by stimulated emission of radiation. An active material capable of producing stimulated emission of radiation is suitably disposed in a chamber with the active material characterized by having at least three distinct energy levels, two of which have a separation in the wave spectrum 60 band of energies correspondent to the frequencies of interest. Pumping means wholly chemical in nature are provided for pumping the active material so that the populations of the separated energy levels are inverted from their normal relation. The pumping means generates light energy of high intensity to provide pumping energy to the active material for producing a high energy output light beam.

Referring to the drawings and in particular to FIGS. 1 and 2, there is illustrated a sectional view of a laser device according to the principles of this invention. The device includes an active material 11 shown in FIG. 1, for example, as a cylindrical rod made of ruby. The rod 11 has a pair of partially reflective silver mirrors at the ends thereof providing the resonant structure to enhance the radiation produced in the active material 11. The end 12, for example, may have a heavy silver coat to make it an opaque mirror while the end 13 may have a silver coat to make it a partially reflecting mirror in the range of 90 to 95%. Pumping energy for the active material 11 is provided by a plurality of pumping sources 14 symmetrically disposed about the active material 11 for generating high intensity light energy to be distributed to the active material 11. Each of the pumping sources 14 is wholly chemical in nature and may comprise, for example, as shown in FIG. 1, a flash powder which is detonated upon excitation from an electrical source 15 series-connected to the pumping sources 14. The active material 11 and pumping sources 14 are suitably disposed in a holding chamber 16 which is filled with an oxidizing gas such as oxygen supplied from the gas source 17. The active material 11 may be enclosed within a protective sheet 18 of quartz or the like to cool the active material as well as provide the proper filtering of the light energy from the pumping sources 14.

In operation of the laser device of FIG. 1, the pumping sources 14 respond [responsive] to a signal from the electrical source 15 to produce a chemical combustion which creates light energy which is directed through the transparent sides of the active material 11 to provide the pumping energy therefor [therefore]. The characteristics of the chemical combustion of the pumping sources 14 are such that the active material 11 receives a pumping pulse with high intensity and a short rise time. The intensity of the light energy from the pumping sources 14 causes the active material 11 to produce a beam of light energy through the partially reflective end 13 of high intensity as well as possessing the well known monochromatic and coherent characteristics of an output beam from a laser.

Referring now to FIGS. 3 and 4, an aspect of the invention is illustrated in which an elliptically shaped chamber 21 encloses an active material 22 and a pumping source 23. The pumping source 23 is entirely chemical in nature and may be detonated without the use of an electrical source such as by a percussion cap. The active material 22, which may comprise a cylindrical rod of the ruby type, has its axis coinciding with the focal axes of the elliptical planes transverse to the length of the chamber 21. In this manner, light energy generated by the detonation of the explosive 23 or by flash powder is focused on the active material 22 in such a manner as to provide a higher intensity light energy pumping source. The active material 22 responsive to the pumping source then produces an output beam of high intensity.

Referring now to FIG. 5, there is illustrated an aspect of the invention in which the pumping source is in the form of an explosive sheet 26 symmetrically spaced around an active material 27. Upon detonation the explosive sheet 26 provides high intensity [in] pumping light energy which is directed toward the center of the active material 27, thereby increasing the intensity of the pumping source.

In the device of FIG. 5, the chamber 28 is filled with an inert gas such as xenon or argon or any easily ionizable vapor. The detonation of the explosive 26 generates a shock wave which is directed toward the axis of the active material 27. The inwardly directed shock wave ionizes the argon or xenon molecules in the chamber 28. The ionized gas radiates high intensity light energy to the active material. In this manner a pumping pulse is received by the active material 27 of extremely high intensity and 75

rapid rise time, causing the emission of a correspondingly high intensity light beam from the active material 27.

Referring now to another aspect of the invention, there is illustrated in FIG. 6 a laser 41 in which light energy for pumping is generated by the ignition of an explosive charge 42 in a shock tube 43. The tube 43 may be constructed of a tough glass material 44 with one end 51 containing the explosive charge 42 and having an outer [a] reinforcing barrel 45. A laser material 46, which may be a ruby rod, is centrally disposed within the tube at the other end 52 of the tube 43. A steel rod 47 connects the laser rod 46 to the end 51 of the tube 43. An inert [A] gas such as xenon fills the space in the tube 43 surrounding the rod 46. Ignition of the explosive charge 42 by a primer 48 causes a shock wave to be created in the xenon gas. The shock wave ionizes the xenon gas as it propagates [propogates] down [to] the tube 43, creating light energy which is directed to the rod 46. The inner surface of the tube 43 may be silvered to reflect the light back into the rod 46. The end 52 may comprise a blowout support which acts as a safety valve if [assuming that] the pressure generated by the explosion in the tube 43 exceeds [does not go beyond] predetermined safety limits. A window 53 passes the light energy produced by the rod 46.

The shock tube pumping system of the laser of FIG. 6 generates a shock wave of high velocity which ionizes the xenon gas to provide [provides] an extremely short [fast use time] pulse of light energy. In FIG. 7, there is shown another method of generating a shock wave of high velocity according to the shock tube pumping system of FIG. 6. The laser 61 of FIG. 7 generates a shock wave in a tube by means of a chamber 62 filled with a gas, such as helium, which ionizes in response [is responsive] to the detonation of an explosive charge 63 in the chamber. When the pressure of the gas reaches a predetermined level [amount], a diaphragm 64 bursts, releasing a light emitting shock wave into the area surrounding the laser rod 65.

The principles of the present invention embodied in the drawings may be utilized in monochromatic lasers of the infrared, visible, or ultra violet wavelengths [wave lengths]. These devices are capable of amplifying or producing energy of the aforesaid wavelengths [wave lengths] with no significant change in the wave of phase thereof. An output light beam from laser devices with high intensity may readily be focused to a point by well known optical means to provide a high intensity light source.

The output of the laser devices according to this invention may be focused by optical means to points in space over long distances to provide [with] a large quantity of energy concentrated at a point. In this manner a laser radiation weapon may be readily provided which will operate at distances heretofore unattainable in the laser field.

Although the invention has been described and illustrated in detail, it is to be clearly understood that the same is by way of illustration and example only and is not taken by way of limitation, the spirit and scope of this invention being limited only by the terms of the appended claims.

I claim:

1. A laser for producing light at high energy levels comprising [ ]:

a rod of active material capable of producing stimulated emission of radiation,

said rod having [end] partially reflective end mirrors for enhancing radiation at a particular [said] frequency [of interest], one of said end mirrors [means] being adapted to pass a light beam from said rod,

and means for pumping said rod of active material comprising a cylindrical sheet of explosive material symmetrically spaced around said rod of active ma-

terial and including an ionizable [ionizing] gas surrounding said rod.

2. A laser for producing light at high energy levels, comprising:

a closed container containing an ionizable gas, means for producing a chemical reaction explosion in said container for creating a shock wave therein to induce ionization of said gas, and thereby cause said gas to produce intense broadband radiation, and a rod of active material capable of producing coherent radiation at a single frequency in response to said broadband radiation, said rod being positioned to receive said broadband radiation from said gas.

3. The laser of claim 2 wherein said rod is positioned within said container containing said gas and wherein said means for producing a chemical reaction explosion comprises a quantity of explosive material within said container.

4. The laser of claim 3 wherein said explosive material is in the form of a cylindrical sheet symmetrically spaced around said rod of active material and adjacent the wall of said container.

5. The laser of claim 3 wherein said container is cylindrically shaped and said rod is mounted on the axis of said container and wherein said explosive material is positioned adjacent one end of said container.

6. The laser of claim 2 wherein said rod is positioned outside said container adjacent one wall thereof, said one wall of said container having insufficient strength to contain said chemical reaction explosion, whereby said wall will burst in response to said explosion and thereby re-

lease a radiation-emitting shock wave of ionized gas to envelop said rod.

7. The laser of claim 6 wherein said container is a cylinder, said one wall thereof is an end of said cylinder, and said rod is positioned along an extension of the axis of said cylinder in a chamber adjacent the outside surface of said wall.
